UNITED STATES PATENT OFFICE.

LAWRENCE J. ZAHN, OF ASTORIA, NEW YORK, ASSIGNOR TO THE INTERNATIONAL POSTAL SUPPLY COMPANY, A CORPORATION OF NEW YORK.

INKING MECHANISM FOR PRINTING MACHINES.

Application filed November 3, 1923. Serial No. 672,493.

To all whom it may concern:

Be it known that I, LAWRENCE J. ZAHN, a citizen of the United States, and a resident of Astoria, county of Queens, city and State 5 of New York, have invented certain new and useful Improvements in Inking Mechanism for Printing Machines, of which the following is a specification.

This invention relates to inking mechanism for printing machines and has for its primary object to provide simple and positive means for insuring a constant uniform supply of ink to the type characters of a printing die or cylinder, certain subject matter claimed herein being disclosed in my prior application for patent filed June 19th, 1923, Ser. No. 646,372, entitled "Check endorsing machine."

As shown in my application above referred to, I provide an absorbent inking roller mounted and arranged to rest by gravity upon a revolute printing die and driven by frictional contact therewith. The novel feature of my present disclosure resides in the provision of an ink receptacle having a continuous spiral blade rotatably mounted therein and frictionally contacting with the absorbent ink applying roller. In the preferred embodiment of the invention, 30 I preferably mount the ink receptacle and said spiral blade for bodily movement relative to the absorbent roller and provide means to yieldingly hold said blade in peripheral contact with the roller.

It is another object of my invention to provide an inking mechanism of this character wherein the ink receptacle is divided by a central partition into two ink receiving compartments adapted to receive inks of 40 relatively different colors and a spiral ink applying blade rotatably mounted in each of these compartments for contact with the absorbent material of the inking roller. This roller is provided with a central annular barrier which prevents the flow of ink from one section of the absorbent material into the other.

With the above and other objects in view, the invention consists in the improved inking mechanism and in the form, construction and relative arrangement of the several parts as will be hereinafter more fully described, illustrated in the accompanying drawings and subsequently incorporated in the sub- 55 joined claims.

In the drawing wherein I have illustrated one simple and practical embodiment of the invention and in which similar reference characters designate corresponding parts throughout the several views:

Figure 1 is a top plan view of the inking mechanism;

Figure 2 is a section taken on the line 2-2 of Figure 1; and

Figure 3 is a detail fragmentary elevation showing the mounting of the ink receptacle and the rotatable ink supplying blade.

In the accompanying drawing, I have illustrated the rotatable printing die 5 of the check endorsing mechanism shown in my prior application above identified. However, it will be understood that the improved inking mechanism is not necessarily limited in its utility to such a machine but by resorting to obvious mechanical modifications, it might also be readily adapted for use in connection with various other types of printing machines. The parts of the inking mechanism are supported in a substantially 75 U-shaped frame or yoke 6 the horizontally disposed arms 7 of which embrace the inking roller 8, said roller having suitable trunnions 9 at its opposite ends journaled in the ends of said frame arms. Each of 80 these frame arms is also formed upon its outer side with a suitable guide 10 to loosely receive a standard or post 11 fixed to a base plate 12'. It will be understood that these posts or standards loosely support the frame 85 6 and the parts mounted therein so that the inking roller 8 rests by gravity upon the periphery of the printing die 5, as shown in Figure 2 of the drawing.

At the opposite side of the roller 8 with 90 respect to the printing die 5, the arms 7 of the frame are integrally connected by the transverse bar 12, each of said arms being also formed with a depending part 13. The lower ends of these depending parts 13 are 100 provided with the obliquely inclined slots 14 through which the opposite ends of the shaft 15 extend. This shaft is also rotatably supported in a fluid-tight stuffing box of any preferred construction provided in 105 a partition plate 16 which centrally divides the ink receptacle 15 into the two non-communicating compartments 17. This receptacle is of elongated trough-like form and is loosely suspended from the shaft 15, the 110

body wall of said trough at its lowermost point being weighted in any suitable manner as indicated at 18 so that it will at all times assume a perpendicular position relative to the axis of the shaft 15.

The shaft 15 has two spirals 19 fixed thereon and extending in the same direction, one of these spirals operating in each of the compartments 17. The spirals may be secured upon the shaft 15 in any preferred manner, but for convenience, I preferably turn a coarse spiral thread or groove in the periphery of the shaft and secure therein a series of spiraled annular discs or plates, the ends of adjacent plates being welded or otherwise secured to each other so as to thus produce a continuous spiral.

It will be noted from reference to Figure 2 of the drawing that the central partition 16 in the ink receptacle or trough extends above the upper edges of the trough walls, such upwardly extending portion of the partition having its edge disposed in the same plane as the peripheral edges of the spirals 19.

The inking roller 8 consists of a suitable core upon which the two felt layers 20 of suitable thickness are secured. These felt layers are divided or separated from each other by a central ring or annulus 21 which may be of celluloid or other preferred material, said ring or annulus being of sufficient thickness to present an impassable barrier which will effectually prevent the flow of ink from one of the felt sections 20 to the other.

To the opposite ends of the shaft 15 exteriorly of the frame 6 the ends of contractile springs 22 are loosely connected, the other ends of the springs being suitably attached to the side arms 7 of the frame. These springs act to pull the shaft 15 and ink receptacle 15' upwardly, thereby holding the peripheral edges of the spirals 19 in frictional contact upon the felt sections 20 while the edge of the upwardly extending portion of the partition wall 16 contacts with the separating barrier 21 between the felt sections.

In the transverse bar 12 of the supporting frame 6 I provide the ink filler cups 23 for convenience in filling the compartments 17 of the ink receptacle.

In the printing of endorsements upon checks it is frequently desirable to have one part of the endorsement appear in one color and the other part in a contrasting color. Thus in the operation of the present invention, blue ink may be placed in one of the partitions 17 and red ink in the other. As the printing die 5 rotates, rotation is transmitted to the ink absorbent roller 8 which, in turn, by its frictional pressure on the edges of the spirals 19, rotates the latter. The lower portions of these spirals extend

ing into the ink in the compartments 17 carries the ink upwardly so that it is distributed longitudinally upon the felt sections 20 and absorbed thereby. The spirals are of such pitch that the felt sections 20 are substantially uniformly saturated with the ink throughout their area. However, by reason of the central barrier 21 on the inking roller, the differently colored inks are segregated from each other. These saturated felt sections 20 contacting with the printing die 5 apply ink of one color to a part of the type characters on the die while ink of a contrasting color is applied to the remaining type characters. Therefore, the impression made by the rotating die upon the paper check as it passes through the machine will appear with the desired portions thereof in the different colors.

From the foregoing description considered in connection with the accompanying drawings, it will be seen that I have produced a novel inking mechanism which is of very simple construction and positive and reliable for the purpose in view. While I have referred to an arrangement whereby the impression is made in differently colored inks it will be understood that in so far as the structural features of my present disclosure are concerned, the device might also be employed for printing in ink of only one color. Likewise although I have referred to a particular mounting and arrangement of the parts of the inking mechanism, this also might be modified as to its several detail features in accordance with the particular purpose for which the printing machine is to be employed and the construction and arrangement of the parts of the printing mechanism. Therefore, while I have herein shown and described one simple and practical embodiment of the device, it is nevertheless to be understood that the essential features of my present disclosure might be embodied in various other alternative constructions. I accordingly reserve the privilege of resorting to all such legitimate changes in the form, proportion and relative arrangement of the several parts as may be fairly embodied within the spirit and scope of the invention as claimed.

I claim:

1. An inking mechanism for printing machines comprising a frame, an absorbent inking roller mounted in said frame and adapted for engagement with a rotatable printing member, a rotatable ink applying member also mounted in said frame, a counterbalanced ink receptacle pivotally suspended from the axis of said ink applying member, and means tending to move said ink applying member and the receptacle as a unit with relation to said frame in a radial direction with respect to the inking roller to maintain the ink applying member

in frictional contacting engagement with the periphery of said inking roller.

2. An inking mechanism for printing machines comprising a frame, an absorbent inking roller mounted in said frame and adapted for engagement with a rotatable printing member, a rotatable ink applying member mounted in said frame and having its axis shiftable in an angular direction 10 radially of said inking roller, a counterbalanced ink receptacle suspended from the axis of said ink applying member, and springs connected with the ends of said axis tending to move said ink applying member 15 and the receptacle as a unit in the frame and maintain said member in frictional bearing contact upon the periphery of the inking roller.

3. In combination with a rotatably 20 mounted printing die, guide standards, a frame loosely engaged with said standards, an absorbent inking roller rotatably mounted in said frame and frictionally contacting with the die to be rotated thereby, an ink 25 receptacle and ink applying means mounted

in the frame for movement relative thereto, and means yieldingly urging the receptacle and ink applying means in one direction to hold the latter in bearing contact upon the periphery of said ink absorbing roller. 30

4. In combination with a rotatably mounted printing die, inking mechanism therefor including a frame, an ink absorbing roller mounted in the frame and bearing upon said die to be rotated thereby, said 35 roller having spaced ink absorbing sections, an ink receptacle mounted in said frame and having a central partition dividing the same into compartments, a rotatable spiral mounted in each of said compartments and 40 frictionally contacting with one of the ink absorbing sections of said roller to be rotated thereby and apply the ink from one compartment to the roller section, and a barrier interposed between said absorbent 45 sections of the inking roller.

In testimony that I claim the foregoing as my invention, I have signed my name hereunder.

LAWRENCE J. ZAHN.
